UNITED STATES PATENT OFFICE.

STANLEY W. NICHOLSON, OF TOLEDO, OHIO, ASSIGNOR TO THE DURA COMPANY, OF TOLEDO, OHIO, A CORPORATION OF DELAWARE.

WINDOW REGULATOR.

Application filed August 25, 1924. Serial No. 734,123.

The invention relates to window regulators and refers more particularly to mechanisms for raising and lowering the windows or closures of vehicle bodies. One of the objects of the invention is to provide a window regulator having an improved means for locking the window in its adjusted positions. Other objects of the invention reside in the novel features of construction and combinations and arrangements of parts as more fully hereinafter set forth.

In the drawings:

Figure 1 is an interior elevation of a vehicle door equipped with a window regulator having an irreversible driving mechanism embodying my invention;

Figure 2 is an enlarged vertical section through a portion of Figure 1, showing the window regulator in elevation.

Figure 3 is a cross section on the line 3—3 of Figure 2;

Figure 4 is a cross section on the line 4—4 of Figure 3;

Figure 5 is a perspective view partly in section of a portion of the irreversible driving mechanism.

As shown in the present instance 1 is the door of a motor vehicle having in its upper portion the opening 2 and in its lower portion the chamber 3. 4 is a window or closure for the opening 2 vertically slideable in guideways in the door into the chamber 3. 5 is a lifter arm suitably connected at its outer end to the window to raise and lower the same and suitably connected at its inner or pivotal end to a toothed member 6 for swinging the arm.

For the purpose of raising and lowering the window 4 and also maintaining this window in its adjusted positions, I have provided an irreversible driving mechanism between the handle 7 and the toothed member 6. In detail, 8 is an anchorage member suitably mounted upon the door and 9 and 10 are cooperating driving and driven shaft sections respectively connected to the handle 7 and the toothed member 6. The driving shaft section 9 has at its inner end the polygonal portion 11 which is engageable in a correspondingly shaped aperture in the handle 7, the adjacent cylindrical portion 12, which is journaled in the anchorage member 8 and the segmental portion 13 which is spaced from the anchorage member. The driven shaft section 10 has at its outer end the

gear member or pinion 14 which meshes with the toothed member 6, the adjacent cylindrical portion 15, which is journaled in the anchorage member 8 and the segmental portion 16, which is spaced from the anchorage member. The segmental portions 13 and 16 overlie each other and have the same axis of rotation and their outer peripheries have the same radius of curvature.

17 is a pin extending axially of the driving and driven shaft sections and preferably having headed ends for connecting these sections to each other. This pin has a diameter equal to the width of the space between the segmental portions 13 and 16 and as a consequence holds these segmental portions in correct spaced relation to each other.

The driving and driven shaft sections 9 and 10 respectively may be readily manufactured from a single piece of stock which is formed to provide the polygonal portion 11 and the cylindrical portion 12 at one end, the gear member or pinion 14 and the cylindrical portion 15 at the other end, and an intermediate cylindrical portion. This stock is also bored to receive the pin 17. However, before insertion of this pin 17 the stock is longitudinally cut by suitable means such as a saw, the slot 19 formed by the cutting terminating short of its ends. The stock is also transversely cut at 18 and 20 to separate the segmental portion 13 from the cylindrical portion 15, and the segmental portion 16 from the cylindrical portion 12 respectively, and also to form two separate members, namely the driving and driven shaft sections. The connecting pin is then inserted and secured in place.

21 is a coil spring having inturned ends 22 and 23 on opposite sides of the pin 17 and engaging in the space between the segmental portions 13 and 16 of the driving and driven shaft sections. These inturned ends are of a diameter less than the width of the space to provide clearance. The convolutions of this coil spring surround the segmental portions of the shaft sections within the anchorage member 8 and have an external diameter slightly less than the internal diameter of the anchorage member to provide sufficient clearance to permit rotation of the driven shaft section 10 upon rotation of the driving shaft section 9 through either of the inturned ends of the coil spring.

- However, if the driving shaft section were stationary and rotation of the driven shaft section in either direction were attempted this driven shaft section coming into contact with either of the inturned ends of the coil spring would expand the latter so that its convolutions frictionally engage and bind upon the anchorage member thereby holding the driven shaft section from rotation.
- 10 From the above description it will be seen that I have provided a simple efficient form of locking device for retaining a window in its adjusted position and also that I have provided a locking device which may be 15 manufactured at a relatively low cost.
- What I claim as my invention is:
1. In a window regulator, the combination of an anchorage member, a driven member operatively connected to a window, a driving member overlying said driven member, and a spring member having ends freely engaging between said driving and driven members, and an intermediate portion between one of said members and said anchorage 25 member and engageable with the latter.
  2. In a window regulator, the combination of an anchorage member, a driven member operatively connected to a window having a portion journaled in said anchorage member, a driving member having a portion journaled in said anchorage member and another portion overlying and spaced from a portion of said driven member and a spring member having inturned ends freely 35 engaging the space between the overlying portions of said driving and driven members and an intermediate portion between one of said members and said anchorage member and engageable with the latter.
  3. In a window regulator, the combination of an anchorage member, a driven member having a toothed portion for operatively connecting said driven member to the window, another portion journaled in said anchorage member and a segmental portion spaced from said anchorage member, a driving member having a portion journaled in said anchorage member and a segmental portion spaced from said anchorage member and overlying and spaced from the first mentioned segmental portion, an axial pin 45 connecting said members and a spring member having inturned ends freely engaging in the space between the segmental portions and an intermediate portion between one of the segmental portions and said anchorage member and engageable with the latter.
  4. In a window regulator, the combination of an anchorage member, a driven shaft section operatively connected to a window and having a portion journaled in said anchorage member and a segmental portion, a driving shaft section having a portion journaled in said anchorage member and a segmental 55 portion overlying and spaced from said first

mentioned segmental portion, a common means for securing said driving and driven shaft sections to each other and for positioning the segmental portions thereof, and a spring having inturned ends freely engaging in the space between the segmental portions and an intermediate portion between one of the segmental portions and said anchorage member and engageable with the latter.

5. In a window regulator, the combination of means for lifting a window including a toothed member, an anchorage member, a driven section connected to said toothed member and having a portion journaled upon said anchorage member, a driving section overlying said driven section and having a portion journaled upon said anchorage member, and a spring having ends engaging between said sections and an intermediate portion between one of said sections and said anchorage member and engageable with the latter.

6. In a window regulator, the combination of means for lifting a window including a toothed member, and an irreversible driving mechanism therefor which turns freely when actuated to turn said toothed member but which locks when said toothed member is turned to actuate said mechanism, said mechanism including an anchorage member, a driven shaft section connected to said toothed member, a driving shaft section overlying said driven shaft section, and a spring having ends engaging between said shaft sections and an intermediate portion between one of said shaft sections and anchorage member and engageable with the latter.

7. In combination with a support, a driven member having a portion journaled in said support and an integral portion spaced from said support, a driving member having a portion journaled in said support and an integral portion spaced from said support and overlying and spaced from said first-mentioned integral portion and a member surrounding said integral portions and having inturned ends extending in opposite directions and freely engaging in the space between said integral portions and also having an intermediate portion between one of said integral portions and said support and engageable with the latter.

8. In combination with a support, a driven member having a portion journaled in said support and an integral portion spaced from said support, a driving member having a portion journaled in said support and an integral portion spaced from said support and overlying and spaced from said integral portion, an axial opening connecting said driving and driven members and a coiled member having inturned ends on opposite sides of said opening and freely engaging in the space between said integral portions,

said coiled member also having an intermediate portion between one of said integral portions and engageable with the latter.

9. In the manufacture of an irreversible driving mechanism, forming a member with longitudinally spaced cylindrical portions and an integral intermediate portion, severing the intermediate portion into two laterally spaced parts by a longitudinal cut and

severing opposite ends of the laterally spaced parts by transverse cuts, intersecting the longitudinal cut whereby cooperating separate members having overlying spaces are formed, each having a cylindrical portion and an integral portion adapted to overlie the integral portion of the other member.

In testimony whereof I affix my signature.

STANLEY W. NICHOLSON.
